UNITED STATES PATENT OFFICE.

LOUIS J. ANDERSEN, OF DECORAH, IOWA:

CHECK-HOOK.

SPECIFICATION forming part of Letters Patent No. 654,582, dated July 31, 1900.

Application filed March 24, 1900. Serial No. 10,065. (No model.)

To all whom it may concern:

Be it known that I, LOUIS J. ANDERSEN, a citizen of the United States, residing at Decorah, in the county of Winneshiek and State 5 of Iowa, have invented certain new and useful Improvements in Check-Hooks; and I do hereby declare the following to be a full, clear, and exact description of the invention, such as will enable others skilled in the art to which 10 it appertains to make and use the same.

My invention relates to harness attachments, more particularly to what is commonly designated as a "check-hook."

The object of my invention, as will be hereinafter fully set forth, is to provide a simple, cheap, though reliably efficient means whereby the checkrein may be safely secured and quickly released at will.

A further object is to provide the body of. 20 my hook with means to reinforce the flexible body of the gig-saddle.

Other objects and advantages will be made fully apparent in the following specification and the accompanying drawings, in which—

25 Figure 1 is a perspective view of my invention as applied to use upon the back-band or upon a flexible gig-saddle of the usual or any preferred construction. Fig. 2 is a side elevation of my check-securing device complete 30 and separated from the back-band or gig-saddle. Fig. 3 is a similar view showing a portion of the body-section broken away, revealing the interior parts thereof. Fig. 4 is a top plan view of my check-securing device 35 complete.

In order to conveniently refer to the several details of my invention and other coöperating accessories, figures will be employed, of which—

40 1 designates the body portion of my check-hook, which may be made of any preferred shape, and is partly tubular in order to provide a seat for securing the interior parts, which will be hereinafter particularly referred to. The body-section 1 is preferably integral with the base-section 2, the opposite end of the base-section being extended upward and shaped to form the curved member or hook 3. To the under side of the base-section 45 thus or otherwise formed I attach to or form integrally therewith the depending anchoring-stem 4, which is threaded at its lower

end and thereby adapted to extend through a suitable aperture provided in the gig-saddle, where it may be secured by means of the 55 locking-nut 5. The body-section 1, as above stated, is partly tubular, thereby providing the chamber 6, within which I dispose the controlling-spring 7, designed to encircle the stem 8, preferably forming an integral part 60 of the thumb-piece 9, the latter being provided with the forwardly-extending finger 10, designed to coöperate with the extreme end of the hook-section 3, it being understood that the meeting ends of said finger and hook-section are to be properly beveled, as clearly 65 shown in Fig. 4, in order to prevent the said finger from moving past the ends of the hook.

In order to securely though rotatively anchor the stem 8 in position, I extend the same 70 loosely through a suitable aperture in the bottom section 11, when I place on the end of said stem as it protrudes through the said aperture the washer 12. The end of the stem 8 may then be upset in the usual way, thereby 75 securing the washer 12 in place and preventing the casual withdrawal of the stem and at the same time insure that the thumb-piece 9, with its finger 10, will be reliably held in its 80 position.

It will be understood that the ends of the spring 7 shall be so secured that the finger 10 will be held normally and tightly against the beveled end of the hook 3, thereby insuring that when the rein is placed within the said 85 hook it will be reliably held in place until the finger 10 has been moved laterally sufficiently to permit said rein to be withdrawn.

In order to make the body portion 13 of the gig-saddle of leather, I am able to reinforce 90 said body portion by means of the spring section or member 14, which is properly shaped or curved, so as to lie snugly in contact with the outer surface of the body portion, though it will be understood that said spring-section 95 14 may be properly embedded within said body. In order to more reliably anchor the check-hook in place, I prefer to securely attach the body of my hook to the middle portion of said spring 14, as by forming an aperture in the spring adapted to receive the stem 4 or otherwise. Each end of the spring-section 14 is provided with an aperture 15, designed to receive the stem of one of the 100

turrets 16, and it is clear that said turrets will firmly hold the spring in place, and thus reliably anchor the check-hook in position on the gig-saddle and at the same time reinforce 5 the body of the saddle when the latter is formed of flexible material.

In Fig. 1 I have indicated the gig-saddle as being formed of a single metal plate 13, provided in the usual manner with the turrets 16, and it is therefore obvious that my securing device for checkreins may be very reliably anchored in its operative position by upsetting the stem 4 within a suitable aperture provided in the gig-saddle thus or otherwise 15 formed and locking the same when so adjusted by means of nut 5, or said nut may be entirely dispensed with by simply upsetting the end of the stem 4 as it protrudes through the plate forming the gig-saddle.

20 By referring to Figs. 2 and 3 it will be observed that the thumb-piece 9 is provided with the semispherical cap or cover 17, which is made of proper shape to provide a finish for the body-section 1, thereby enabling my 25 attachment to present a desirable appearance and finish, inasmuch as all of the parts may be neatly finished in any preferred way.

Since the tension of the spring 7 is normally directed toward the end of the hook 3, it will 30 be understood that the finger 10 will be disposed tightly against the said end, thereby reliably securing the strap placed in the keeping of the said hook-section. When it is desired to secure the rein, the thumb-piece 9 is 35 so manipulated that finger 10 will be moved laterally out of contact with the end of hook 3, when the rein may be readily dropped in place. By releasing the thumb-piece the spring 7 will force the finger 10 tightly against 40 the end of the hook 3, thereby locking the rein in a secure position. If desired, the spring-section 14 may be dispensed with and the body of my check-hook attached directly to the gig-saddle by the stem 4, and I therefore 45 desire to employ said spring 14 or entirely omit it, as I may find most desirable in practice.

While I have described the preferred construction of my improved securing device, it 50 will be understood that I desire to comprehend in this application all such equivalents thereof as may fall fairly within the scope of my invention. I do not therefore wish to

be strictly confined to the exact showing herein made.

Having thus fully described my invention, what I claim, and desire to secure by Letters Patent, is—

1. The herein-described check-hook comprising a body portion; a hook-section 3; a thumb-piece having a finger designed to co-operate with the end of said hook and suitable means to hold said finger normally in engagement with said hook, in combination with a curved spring 14 secured to said body 65 and having an aperture in each end, all combined substantially as specified and for the purpose set forth.

2. A check-hook having a tubular portion and a forwardly-extending hook-section; a thumb-piece having a stem extending through the body portion; a spring surrounding said stem; a finger carried by said thumb-piece and designed to co-operate with the end of said hook whereby through the action of said 75 spring the said finger will be held normally in engagement with the end of said hook substantially as specified and for the purpose set forth.

3. The combination with a gig-saddle having a flexible body, of a check-hook comprising a body portion, a base having a spring secured thereto adapted to reinforce said flexible body, a hook-section 3, a thumb-piece having a finger designed to co-operate with 85 said hook; and means to hold said finger normally in contact with the free end of said hook, as and for the purpose set forth.

4. The herein-described check-hook for harness, comprising a body-section; a spring-section 14; a base; a hook-section and an anchoring-stem in combination with a thumb-piece having a forwardly-extending finger, the free end of which is beveled to co-operate with the end of the said hook and a controlling-spring designed to actuate said thumb-piece and finger and hold the latter in such a position that said hook will be normally closed, all combining substantially as specified and for the purpose set forth.

In testimony whereof I affix my signature in presence of two witnesses.

LOUIS J. ANDERSEN.
